FIG.1

FIG.4

FIG.2

FIG.3

FIG. 5

FIG. 6

FIGURE 1 is a perspective view of a table according to the embodiment of my inventive design;

FIGURE 2 is a side view of the table shown in FIGURE 1 and the view from the other side of the table is the same as FIGURE 2;

FIGURE 3 is an end view of the table shown in FIGURE 1 and the view from the other end of the table is the same as FIGURE 3;

FIGURE 4 is a perspective view on an enlarged scale of a corner of the table as shown in FIGURE 1;

FIGURE 5 is a view of a portion of the table shown in FIGURE 1 showing one of the legs of the table in perspective, looking edge on from the interior of the table; and

FIGURE 6 is a view of a portion of the table shown in FIGURE 1 showing one of the legs of the table in perspective, looking side on from the interior of the table.

The characteristic feature of this design resides in a table having a composite leg including an insert facing generally toward an interior table portion and providing a longitudinally extending exterior wall means of generally V-shaped configuration facing toward said interior portion of said table, all as best illustrated in FIGURES 5 and 6.

I claim:

The ornamental design for a table, substantially as shown and described.
